UNITED STATES PATENT OFFICE.

CHARLES H. SMITH AND EDWARD JONES, OF MILWAUKEE, WISCONSIN.

DRY-GOODS SAMPLE AND TICKET HOLDER.

SPECIFICATION forming part of Letters Patent No. 714,249, dated November 25, 1902.

Application filed October 2, 1901. Serial No. 77,838. (No model.)

To all whom it may concern:

Be it known that we, CHARLES H. SMITH and EDWARD JONES, citizens of the United States, residing at Milwaukee, county of Milwaukee, 5 and State of Wisconsin, have invented new and useful Improvements in Dry-Goods Sample and Ticket Holders, of which the following is a specification.

Our invention relates to improvements in 10 that class of sample and ticket holders which is used for holding samples and price-marks of various kinds and qualities of dry goods and which is adapted when provided with samples of goods and price-marks, &c., to be 15 inserted in the center or between the folds of a bolt of cloth.

Our improvement pertains more especially to the peculiar construction of the holder, whereby the same, with the exception of the 20 elastic fabric-retaining bands and the bar at the rear end, is adapted to be cheaply and quickly made from a single piece of sheet metal.

The construction of our device is further 25 explained by reference to the accompanying drawings, in which—

Figure 1 represents a longitudinal section thereof. Fig. 2 is an end view. Fig. 3 is a plan view, and Fig. 4 is a transverse section 30 drawn on line xx of Fig. 3.

Like parts are identified by the same reference-letters throughout the several views.

A represents an ordinary bolt of cloth, which is wound upon a center-board B in the ordinary manner. The sample-holder comprises a flat central piece C and end piece D, formed at right angles to the body of the holder, and two side flanges E E, all of which parts are so formed from a single piece of sheet metal by 35 cutting and bending the same that the use of solder or rivets for uniting the several parts is avoided. The side flanges E E are formed by folding the edges of the plate at right angles thereto and then folding the same back 40 upon itself, as indicated in Fig. 4, whereby the edges of the flanges are given a smooth rounded surface, which facilitates sliding the holder between the folds of cloth, while the folds of the flanges also serve as a convenient 45 means for holding the elastic retaining-bands F in place. The ends of the elastic bands F are inserted between the folds a and b of said

flanges, when said folds are compressed together upon the ends of said bands with sufficient force to securely retain them in place. 55

F' is a fabric-supporting guide-bar which is secured at its respective ends to the opposing walls of the side flanges E. The object of the bar F' is to so support and retain the inner ends of the sample M as to cause the lower 60 fold to be drawn back to the rear end of the case and straightened out before being withdrawn therefrom. To facilitate inserting the holder in the cloth, the rear ends G of said flanges E are folded inwardly and downwardly 65 upon the central portion of the holder in such a manner as to form a gradually-tapered bearing from the front end D of the holder rearwardly to the downward edges of said flanges. The front D of the holder is provided with two card-retaining apertures H for the reception of the price-card I, said card I being inserted in one of said apertures H and out of the other, while the center plate J of 70 said end piece D (behind said price-card) is 75 upset or bent rearwardly slightly a depth corresponding with the thickness of said card, as indicated in Fig. 1, whereby said card may be inserted through said apertures without bending. To prevent the liability of said 75 price-card becoming accidentally disengaged from its retaining-slots, the central plate J is provided with one or more indentations or contact-bearings K, which are formed by indenting said plate with a die from its rear 80 side, so that the convex portion of said bearings will press against the price-card and retain the same in place.

The front portion of the holder is provided with a transverse aperture L for the reception of the end of the sample piece M, which is adapted to be drawn from the holder forwardly through said slot from time to time as samples of the goods are required. The sample M is preferably cut from the front 90 end of the roll of goods in strips corresponding in width with the space between the flanges E of the holder, when it is folded forwardly and backwardly upon itself, as indicated in Fig. 1, and is then inserted upon the 95 under side of the holder, beneath the retaining-bands F, with the free end of said sample 100 preferably arranged next to the surface of the holder. The free end of the sample is

then inserted through the slot L, when the holder and its contained samples are inserted in the bolt of cloth, as indicated in Fig. 1, when the card containing the price-mark is 5 inserted through the slots H of the end piece, as stated.

Having thus described our invention, what we claim as new, and desire to secure by Letters Patent, is—

- 10 1. As a new article of manufacture, a sample-holder for dry goods, comprising a central portion provided with two side flanges and an end piece respectively formed substantially at right angles to said central portion, from a single piece of sheet metal; and a plurality of fabric-retaining bands secured at their ends to the sides of said central portion, as set forth, said side flanges projecting from the central portion and forming bearing- 15 shoes adapted for contact with the winding-board of a bolt of goods.
- 20 2. As a new article of manufacture, a sample-holder for dry goods, comprising a central portion provided with two side flanges and an end piece respectively formed at right angles to said central portion, from a single piece of sheet metal; a plurality of fabric-retaining bands secured at their ends to the sides of said central portion, said end piece 25 being provided with card-retaining slits, and offsets between the slits, as set forth.
- 30 3. As a new article of manufacture, a sample-holder for dry goods, comprising a central portion provided with two side flanges and an end piece respectively formed at right angles to said central portion, from a single piece of sheet metal; a plurality of fabric-retaining bands secured at their ends to the sides of said central portion, said end piece 35 being provided with apertures for the recep- 40

tion of a sample-card; and indentations or contact-bearings adapted to impinge against the surface of the sample-card and retain the same in said apertures, as set forth.

4. As a new article of manufacture, a sample-holder for dry goods, comprising a central portion provided with two side flanges and an end piece formed to extend substantially at right angles to said central portion from one face thereof, the other face forming a smooth and unobstructed plane surface, said plate, flanges and end piece being formed integrally from a single piece of sheet metal; and a plurality of fabric-retaining devices secured at their ends to the sides of said central portion, said side flanges projecting from the central portion in a position to form bearing-shoes for the holder, adapted for contact with the winding-board of a bolt of goods. 45 50 55

5. As a new article of manufacture, a sample-holder for dry goods, comprising a central portion provided with two side flanges and an end piece formed substantially at right angles to said central portion, said side flanges being tapered toward the central portion at the end opposite said end piece; and a plurality of fabric-retaining devices crossing the central portion of the holder between the side flanges, said side flanges being provided with smooth edges and adapted to form 60 65 70 bearings for the holder on the winding-board of a bolt of goods.

In testimony whereof we affix our signatures in the presence of two witnesses.

CHARLES H. SMITH.
EDWARD JONES.
